Held, Saint-Blaise, Neuchatel, Switzerland
Filed July 10, 1962, Ser. No. 208,770
3 Claims. (Cl. 59—79)

My invention has for its object an expandible wrist band including, on the one hand, a spring wire, the shape of which is that which may be obtained by winding a wire helically round a rectangular prism and, on the other hand, two strips of yielding material extending along the longer sides of the spring, one of said strips passing in each successive fraction underneath the longer lower side of one convolution and then over the next successive upper longer convolution side and again underneath the lower side of the second of the latter convolutions, whereas the second strip passes over the lower sides which are left free by the first strip.

I have illustrated by way of example in the accompanying drawings a preferred embodiment of a wrist band according to my invention. In said drawings:

FIG. 1 is a general plan view of the wrist band.

FIG. 2 is a plan view of the spring.

FIG. 3 is an end view of the spring.

FIG. 4 is a diagrammatic elevational view of the wrist band on a larger scale.

The wrist band illustrated includes a spring wire assuming the shape obtained by winding a wire helically round a rectangular prism. Said spring (FIG. 4) is fitted with two strips 2 and 3 of a yielding material such as leather, fabric, plastic material or the like. As illustrated in FIG. 4, the strips are caused to pass through the convolutions of the spring. For instance, the strip 2 passes underneath the lower side 4 of one of two spring convolutions seen endwise, then above the two following upper longer convolutions sides 5 and 6 beyond which it sinks and passes underneath the next lower longer convolution side 7. As to the strip 3, it passes underneath the successive longer lower sides of the convolutions such as 8 which are not engaged by the strip 2, since the latter passes over the corresponding upper side 5 only.

FIG. 4 shows the spring in a slightly expanded condition. If it is still further expanded, the convolutions of the spring move apart, the strips 2 and 3 are elongated and the sag of their undulations is slightly reduced.

What I claim is:

1. An expandible wrist band comprising in combination a wire wound into a flattened rectangular helical coil having a longitudinal axis and forming successive pairs of convolutions each having two major side elements ex-

2

tending transversely of said longitudinal axis and facing opposite directions, a first strip of foldable material looped over the major side elements facing a same direction in the successive pairs of convolutions and wound between any two successive pairs over the major side element facing the other direction in the second convolution of the first of the two successive pairs, and a second strip extending outwardly of the last-mentioned major element facing the other direction of said second convolution of each pair and inwardly of the major element facing said other direction of the first convolution of each pair.

2. An expandible wrist band comprising in combination a wire wound into a flattened helical coil having a longitudinal axis and substantially adjacent convolutions each having opposite longer side elements and shorter connecting elements, and a strip of yieldable material having a width approximately as great as the length of said longer sides of the convolutions, said strip being interlaced with said convolutions of the coil in the manner that it passes outside of successive groups of at least two of said longer elements on one side of said coil and, between said successive groups, it crosses the axis of said coil and passes outside of the longer side element of at least one convolution at the opposite side of the coil.

3. An expandible wrist band comprising in combination a wire wound into a flattened helical coil having a longitudinal axis and substantially adjacent convolutions each having opposite longer side elements which are substantially straight and shorter connecting elements, a first strip of yieldable material interlaced with said convolutions in the manner that it is looped back and forth over longer side elements on opposite sides of said coil and passes outside of all of the said longer side elements at one side of said coil and outside of spaced longer side elements only at the opposite side of said coil, said strip crossing said longitudinal axis in passing back and forth between opposite sides of said coil, and a second strip interlaced with said longer side elements at said opposite side only of said coil and remaining on one side only of said axis, said second strip passing outside of those longer side elements that said first strip passes outside of and inside of intervening longer side elements at the same side of said coil.
